Application June 14, 1937, Serial No. 148,144

19 Claims. (Cl. 312—60)

This invention relates to improvements in cabinets for dispensing paper towels and similar articles.

The principal object of the invention is to reduce waste by discouraging wanton withdrawal of the towels, this object contemplating a cabinet in which provision is made for insuring a delay between the withdrawal of successive towels.

10 A further object is a dispensing cabinet in which provision is made for preventing the accidental withdrawal of two or more towels at a time.

15 A still further object is a novel design and arrangement of the parts of the cabinet whereby simplicity and economy in construction are obtained.

The invention is illustrated in the accompanying drawings in which:

20 Figure 1 is a perspective view of a dispensing cabinet embodying the features of the invention.

Figure 2 is an enlarged vertical section taken along line 2—2 of Figure 1 showing the parts in the positions they occupy when the leading 25 end of the lowermost towel is held in a visible and accessible position.

Figure 3 is a horizontal section taken along line 3—3 of Figure 2.

Figure 4 is a section through the clockwork 30 of the automatic release mechanism and is taken along line 4—4 of Figure 3.

Figure 5 is a fragmentary section taken along line 5—5 of Figure 4.

Figure 6 is a section taken along the same line 35 as Figure 2, showing the parts in the positions which they assume during the withdrawal of a towel.

Figure 7 is a fragmentary section taken along line 7—7 of Figure 1 showing the parts in the 40 same positions in which they are shown in Figure 6.

Figures 8 and 9 are similar sections, the former showing a towel partially withdrawn while the latter illustrates the position in which the 45 succeeding towel is temporarily held after the withdrawal of a towel.

The cabinet, as shown, includes a cover section 8 and a back section 9. It is illustrated, by way of example, in connection with individual towels 10 which are arranged in a magazine 11 and which are folded in conventional manner so that as a towel is withdrawn from the magazine the succeeding towel is advanced to the position originally occupied by it. The magazine 11 includes side walls 12 and 13 (Figure 3) which are suit-

ably secured to the back section 9 and which are spaced inwardly with respect to forwardly directed flanges 15 formed upon said section, the side walls 12 and 13 terminating just short of the front wall of the cover section. The towels 5 are supported upon inclined plates 16 and 17 (Figure 7) the former being arranged beneath the forward edges of the towels while the latter is arranged at a slightly lower elevation beneath the rearmost edges of the towels. The cover section is pivotally connected to the back section by rivets 19 in order to provide access to the magazine, a lock 20 preferably being employed to lock the cover section in its closed position. The opening movement of the cover section is limited by 15 guidepins 21 which are carried by the side walls of the said section and which traverse arcuate slots 22 (Figure 2) formed in the flanges of the back section. The opening through which the towels are withdrawn from the cabinet is indicated at 20 23. It is formed in the front wall of the cover section, being located below the magazine 11 and being defined by the lower marginal edge 24 of the said front wall and the forward edge of the bottom wall 25. Preferably the latter is cut 25 away as indicated at 26 to facilitate grasping the leading ends of the towels.

When they are arranged in the magazine 11 the leading end 27 of the lowermost towel is passed behind a rod 28 (Figure 7) and then inserted between a pair of rods 29 and 30, the said rods being arranged in parallel relation and extending transversely of the cabinet. The rod 28 is carried by a pair of depending arms 31 and 32 which are located at opposite sides of the magazine, the former being mounted for pivotal movement upon a pin 33 which is carried by the wall 12 while the latter is similarly mounted upon a pin 34 which is carried by the wall 13. The rods 29 and 30 are carried by a pair of depending arms 35 and 36 which are likewise located at opposite sides of the magazine 11, the arm 35 being mounted for pivotal movement upon the pin 33 while the arm 36 is similarly mounted upon the pin 34. A spring 37 which is connected at one end to the wall 13 and at its opposite end to the arm 32 normally holds the arms 31 and 32 in positions in which the rod 28 is located in the fold connecting the two lowermost sections of the leading towel as best shown in Figures 7 50 and 9. The arms 35 and 36, on the other hand, normally occupy positions in which the rod 30 holds the leading end of the lowermost towel so that it is visible and accessible through the opening 23.

It will be apparent, therefore, that when the parts occupy the positions shown in Figure 2 the leading end of the lowermost towel may be grasped and pulled to withdraw the said towel from the cabinet, the towel passing behind the rod 28 and between the rods 29 and 30. As the towel is withdrawn its upper two sections and the leading end of the succeeding towel form a bulge 38 (Figure 8) in front of the rod 28. The 10 resistance thus provided by the said bulge causes the rod 28 to move forwardly against the action of the spring 37. This movement of the rod 28 is transmitted to the arms 35 and 36, and hence the rods 29 and 30, by a projection 39 which is carried by the arm 32 and which is engageable with the arm 36, the arms 35 and 36 being moved toward the front wall of the cabinet to carry the rod 29 to a position in which it holds the leading end of the succeeding towel so that it is inaccessible through the opening 23. As the arms 35 and 36 approach the limit of such forward movement a projection 40 on the arm 36 moves under and is engaged by a latch 41 which is pivotally mounted upon the wall 13, thereby latching the 15 said arms in such position. During withdrawal of the towel in the manner described the bulge 38 which is formed in front of the rod 28 is progressively reduced in size. The said rod remains in the position shown in Figure 8 until the 20 bulge is dissipated to a degree which will permit it to return to its original position under the influence of the spring 37, the said rod entering the fold provided by the two lower sections of the succeeding towel as it returns to such position. The return movement of the rod 28 takes place while the arms 35 and 36 are latched at the forward limit of their range of movement and as the fold of the succeeding towel is advanced to the position originally occupied by the 25 corresponding fold of the lowermost towel. Hence, during the final part of the withdrawal movement of the latter towel the rod 28 engages the fold of the succeeding towel to prevent it from being withdrawn from the cabinet or from 30 being moved beyond the position originally occupied by the lowermost towel.

Means is provided for automatically effecting the release of the arms 35 and 36 after a predetermined interval in order to permit them to return by gravity to their original positions, thereby to move the leading end of the succeeding towel so that it is visible and accessible through the opening 23. The said means includes a link 42, the lower end of which carries a lateral projection 42a which is located in an elongated slot 43 formed in the tail-piece 44 of the arm 32. The upper end of the link 42 is connected to an arm 45 which is actuated by clockwork 46. The said clockwork is mounted upon the wall 13 and includes a stationary main shaft 47 and a train of gears 48, 49, 50, 51, 52 and 53 (Figure 4), the arm 45 being pivotally connected at its inner end to the shaft 47 and being suitably connected intermediate its ends to the gear 48. The said 45 gears are actuated by a spring 54, one end of which is connected to the shaft 47 and the other end of which is connected to a casing 55 which is mounted upon the gear 48.

The parts are so designed that when the arms 70 35 and 36 occupy their normal positions the projection 42a of the link 42 is located in the vicinity of the bottom of the slot 43 as best shown in Figure 2. Hence as the lowermost towel is withdrawn and the rod 28 is moved forward in the 75 manner described the movement of the arm 32

is transmitted to the link 42, thereby to move the said link upward. The clockwise movement thus imparted to the arm 45 and hence the gear 48, of the clockwork winds the spring 54, it being noted that as the bulge 38 of the towel releases the rod 28 and permits the arms 31 and 32 to return to their normal positions the tail-piece 44 moves downward relatively to the link 42, thereby positioning the projection 42a in the vicinity of the upper end of the slot 43. Upon release of 10 the projection 42a, however, the spring 54 automatically starts to unwind to return the link 42 to its normal position. This action of the spring 54 is delayed by the gears 48, 49, 50, 51, 52 and 53 and an associated escapement 56, the parts 15 being so designed that a predetermined interval must elapse before the link 42 returns to its normal position. As the said link approaches this position the projection 42a engages a tail-piece 57 of the latch 41 and pivots the latter against the 20 action of a spring 58 to release the projection 40 and permit the arms 35 and 36 to return to their normal positions, the rod 29 directing the leading end of the lowermost towel to the position shown in Figure 2 during such movement. In order to enable a towel to be withdrawn as rapidly as desired a clutch is employed to render the escapement 56 inoperative during winding movements of the spring 54, the said clutch consisting of a ratchet 59 which is carried by the gear 50 30 and which is held in engagement with the gear 49 by a spring 60. During winding movements of the spring 54 the ratchet 59 permits the gear 49 which is loosely mounted on its shaft to rotate freely on said shaft. However, during unwinding movements of the spring 54 the said ratchet locks the gears 49 and 50 against relative angular movement.

From the foregoing it will be apparent that the leading end of the lowermost towel in the magazine is normally visible and may be readily grasped and pulled to withdraw the towel from the cabinet. The movement of the towel as it is withdrawn is utilized to move the rods 29 and 30 to positions in which they will hold the leading end of the succeeding towel so that it is inaccessible through the opening 23. The movement of the towel as it is withdrawn is also utilized to wind the spring of the clockwork 46, the latter being operative automatically to release the arms 35 and 36 after a predetermined interval and permit them to move the leading end of the succeeding towel to a position in which it is visible and accessible through the opening 23. The construction described has the advantage that after one towel has been withdrawn the succeeding towel cannot be withdrawn until the clockwork permits the leading end of the latter to be moved to an accessible position. Wanton and wasteful withdrawal of the towels is, therefore, 60 prevented, it being understood, of course, that the towels which are employed are preferably of a size and material which will render a single towel adequate for ordinary purposes.

In the event that it is desired to render the 65 lowermost towel immediately accessible this may be accomplished by depressing a button 61. The stem 63 of the latter is mounted for axial movement in a lug 62 which is carried by the front wall of the cabinet and terminates in the vicinity 70 of an extension 64 of the latch 41 when the latter engages the projection 40 as shown in Figure 6. Upon operation of the button 61 the latch 41 is pivoted against the action of the spring 58 to release the projection 40 and permit the arms 75

35 and 36 to return immediately to their normal position. In this connection it is to be understood that the manual means for effecting the release of the latch 41 may be employed if desired 5 independently of the automatic release mechanism. In such case it is understood, of course, that the leading end of the lowermost towel will normally occupy a position in which it is inaccessible through the opening 23. When it is desired, therefore, to withdraw a towel from the cabinet the button 61 is depressed to effect the release of the arms 35 and 36 in the manner described. As the towel thus rendered accessible is withdrawn the arms 35 and 36 are again moved 10 to positions in which the leading end of the succeeding towel will be held so as to be inaccessible. The utilization of the manual release mechanism in the manner described has to some degree the same advantages as the automatic release mechanism, the necessity of operating the button 61 15 to effect the withdrawal of each towel tending to discourage the withdrawal of more towels than may be necessary.

I claim as my invention:

25 1. A cabinet for dispensing individual paper towels of the kind which are folded and arranged in such a manner that as a towel is withdrawn from the cabinet a second towel is advanced to the position originally occupied by it, said cabinet having an opening through which said towels are withdrawn, means which is moved by a towel as it is withdrawn to a position in which it holds the leading end of said second towel so that it is inaccessible through said opening, means for 30 holding said first named means in such position and means for actuating said last named means, whereby to effect movement of said first named means to a position in which it holds the leading end of said second towel so that it is accessible 35 through said opening.

2. A cabinet for dispensing individual paper towels of the kind which are arranged and folded in such a manner that as a towel is withdrawn from the cabinet a second towel is advanced to the position originally occupied by it, said cabinet having an opening through which said towels are withdrawn, means which is moved by a towel as it is withdrawn to a position in which it holds the leading end of said second towel so that it is inaccessible through said opening, means for 40 latching said last named means in such position and means for releasing said latching means, whereby to permit said first named means to return to its original position to move the leading end of said second towel so that it is accessible through said opening.

3. A cabinet of the character described having an opening through which the articles to be dispensed are withdrawn and through which access 45 may be normally had to the leading article, means which is moved by said article as it is withdrawn to a position in which it holds the succeeding article so that it is inaccessible through said opening, means for holding said first named means in such position and means which is automatically operative after a predetermined interval for effecting the release of said last named means, whereby to move said succeeding article to a position in which it is accessible through said opening.

4. A cabinet for dispensing toweling, said cabinet having an opening through which said toweling is withdrawn and through which access may be normally had to the leading end of said toweling, means which is moved by said toweling as a

piece of it is withdrawn to a position in which it holds the new leading end of said toweling so that it is inaccessible through said opening, means for holding said first named means in such positions and means which is automatically operative after a predetermined interval for effecting the release of said last named means, whereby to move said first named means to a position in which it holds the new leading end of said toweling so that it is accessible through said opening.

5. A cabinet for dispensing toweling, said cabinet having an opening through which said toweling is withdrawn, means for holding the leading end of said toweling so that it is accessible through said opening, means which is operative 10 as a piece of said toweling is withdrawn to move said first named means to a position in which it holds the new leading end of said toweling so that it is inaccessible through said opening, means for latching said first named means in 15 such position and means which is automatically operative after a predetermined interval for effecting the release of said latching means, whereby to move said first named means to a position in which it holds the new leading end of said toweling so that it is accessible through said opening.

6. A cabinet for dispensing toweling, said cabinet having an opening through which said toweling is withdrawn and through which access may be had to the leading end of said toweling, means which is movable as a piece of said toweling is withdrawn to a position in which it holds the new leading end of said toweling so that it is inaccessible through said opening, means for holding 30 said first named means in such position and clockwork for automatically releasing said last named means after a predetermined interval, whereby to move the new leading end of said toweling to a position in which it is accessible 35 through said opening.

7. A cabinet for dispensing toweling, said cabinet having an opening through which said toweling is withdrawn, means for holding the leading end of said toweling so that it is accessible through said opening, means which is operative 40 as a piece of said toweling is withdrawn to move said last named means to a position in which it holds the new leading end of said toweling so that it is inaccessible through said opening and clockwork for automatically effecting the return of said last named means to its original position after a predetermined interval, whereby to move the new leading end of said toweling to a position in which it is accessible through said opening.

8. A cabinet for dispensing individual paper towels of the kind which are folded and arranged in such a manner that as a towel is withdrawn from the cabinet a second towel is advanced to the position originally occupied by it, said cabinet having an opening through which the towels are withdrawn and through which access may be had to the leading end of the first towel, means which is movable as said first towel is withdrawn to a position in which it holds the leading end of said second towel so that it is inaccessible through said opening, means for holding said first named means in such position and means for actuating said last named means after a predetermined interval, whereby to move the leading end of said second towel to a position in which it is accessible through said opening.

9. A cabinet for dispensing individual paper towels of the kind which are folded and arranged in such a manner that as a towel is withdrawn

from the cabinet a second towel is advanced to the position originally occupied by it, said cabinet having an opening through which the towels are withdrawn, means for holding the leading end of the first towel so that it is accessible through said opening, means which is operative as a towel is withdrawn to move said last named means to a position in which it holds the leading end of said second towel so that it is inaccessible through said opening and clockwork for effecting the return of said last named means to its original position after a predetermined interval, whereby to move the leading end of said second towel to a position in which it is accessible through said opening.

10. A cabinet for dispensing paper towels of the kind which are folded and arranged in such a manner that as a towel is withdrawn from the cabinet a second towel is advanced to the position originally occupied by it, said cabinet having an opening through which the towels are withdrawn, a member which is engageable with the leading end of the first towel to hold it in a position in which it is accessible through said opening, said towel being operative as it is withdrawn to move said member to a second position in which it holds the leading end of said second towel so that it is inaccessible through said opening, means for latching said member in said second position, and means for automatically releasing said latching means after a predetermined interval to permit said member to move the leading end of said second towel to a position in which it is accessible through said opening.

15. 11. A cabinet for dispensing toweling, said cabinet having an opening through which said toweling may be withdrawn, a pair of rods between which said toweling passes, said toweling being operative as a piece of it is withdrawn to move said rods to a position in which they hold the new leading end of said toweling so that it is inaccessible through said opening, means for holding said rods in such positions and means for actuating said last named means, whereby to return said rods to their original positions after a predetermined interval so as to move the new leading end of said toweling to an accessible position.

20. 12. A cabinet for dispensing toweling, said cabinet having an opening through which said toweling may be withdrawn, a pair of rods between which said toweling passes, pivotally mounted arms which carry said rods, said toweling being operative as a piece of it is withdrawn to move said arms to positions in which said rods hold the new leading end of said toweling so that it is inaccessible through said opening, means for latching said arms in said positions and means which is operative after a predetermined interval for releasing said latching means to permit said arms to return to their normal positions and thereby move the new leading end of said toweling so that it is accessible through said opening.

25. 13. A cabinet for dispensing paper towels of the kind which are doubled and folded to provide accordion sections, the leading end of each towel (with the exception of the first) being arranged between the trailing ends of the preceding towel so that as a towel is withdrawn from the cabinet the succeeding towel will be advanced to the position originally occupied by it, said cabinet having an opening through which the towels are withdrawn and through which access may be had to the leading towel, guide means through which said towels pass, a member around which said

30. towels pass, said member being arranged in a fold of said first towel, resilient means for normally holding said member in such position, said member being moved forward by said first towel against the action of said resilient means during withdrawal of the initial part of said first towel and returning to its original position under the influence of said resilient means during the withdrawal of the remainder of said first towel to enter a fold of the succeeding towel and prevent the latter from being withdrawn from said cabinet by said first towel, said member being operative as it is moved forward as described to move said guide means to a position in which the leading end of the succeeding towel is held so that it is inaccessible through said opening, means for holding said guide means in such position and means which is operative automatically after a predetermined interval for releasing said last named means, whereby to move said guide means to position the leading end of said succeeding towel so that it is accessible through said opening.

35. 14. A cabinet for dispensing paper towels of the kind which are doubled and folded to provide accordion sections, the leading end of each towel (with the exception of the first) being arranged between the trailing ends of the preceding towel so that as a towel is withdrawn from the cabinet the succeeding towel will be advanced to the position originally occupied by it, said cabinet having an opening through which the towels are withdrawn, a pair of rods between which said towels pass, a member around which said towels pass, said member being arranged in a fold of said first towel, resilient means for normally holding said member in such position, said member being moved forward by said first towel against the action of said resilient means during withdrawal of the initial part of said first towel and returning to its original position under the influence of said resilient means during the withdrawal of the remainder of said first towel to enter a fold of the succeeding towel and prevent the latter from being withdrawn from said cabinet by said first towel, said member being operative as it is moved forward as described to move said rods to positions in which they hold the leading end of the succeeding towel so that it is inaccessible through said opening, means for holding said rods in such positions and means which is operative automatically after a predetermined interval for effecting the release of said last named means, whereby to move said rods to position the leading end of said succeeding towel so that it is accessible through said opening.

40. 15. A cabinet for dispensing paper towels of the kind which are doubled and folded to provide accordion sections, the leading end of each towel (with the exception of the first) being arranged between the trailing ends of the preceding towel so that as a towel is withdrawn from the cabinet the succeeding towel will be advanced to the position originally occupied by it, said cabinet having an opening through which the towels are withdrawn, a pair of rods between which said towels pass, pivotally mounted arms which carry said rods, a third rod behind which said towels pass, pivotally mounted arms for carrying said third rod, said third rod being arranged in a fold of said first towel, resilient means for normally holding said third rod in such position, said third rod being moved forward by said first towel against the action of said resilient means during withdrawal of the initial part of said first towel and returning to its original position under the influence of said resilient means during the withdrawal of the remainder of said first towel to enter a fold of the succeeding towel and prevent the latter from being withdrawn from said cabinet by said first towel, said member being operative as it is moved forward as described to move said rods to positions in which they hold the leading end of the succeeding towel so that it is inaccessible through said opening, means for holding said rods in such positions and means which is operative automatically after a predetermined interval for effecting the release of said last named means, whereby to move said rods to position the leading end of said succeeding towel so that it is accessible through said opening.

to its original position under the influence of said resilient means during the withdrawal of the remainder of said first towel to enter a fold of the succeeding towel and prevent the latter from being withdrawn from said cabinet by said first towel, said last named arms being operative as said third rod is moved forward as described to move said first named arms to positions in which said first named rods hold the leading end of the succeeding towel so that it is inaccessible through said opening, means for latching said first named arms in such positions and means which is operative automatically after a predetermined interval to release said latching means and permit said first named arms to return to their original positions, whereby to move the leading end of the succeeding towel so that it is accessible through said opening.

16. A cabinet for dispensing paper towels of the kind which are doubled and folded to provide accordion sections, the leading end of each towel (with the exception of the first) being arranged between the trailing ends of the preceding towel so that as a towel is withdrawn from the cabinet the succeeding towel will be advanced to the position originally occupied by it, said cabinet having an opening through which the towels are withdrawn, a member around which said towels pass, said member being arranged in a fold of said first towel and resilient means for normally holding said member in such position, said member being moved forward by said first towel against the action of said resilient means during withdrawal of the initial part of said first towel and returning to its original position under the influence of said resilient means during withdrawal of the remainder of said first towel to enter a fold of the succeeding towel and prevent it from being withdrawn from said cabinet by said first towel.

17. A cabinet for dispensing paper towels of the kind which are doubled and folded to provide accordion sections, the leading end of each towel (with the exception of the first) being arranged between the trailing ends of the preceding towel so that as a towel is withdrawn from the cabinet the succeeding towel will be advanced to the position originally occupied by it, said cabinet having an opening through which the towels are withdrawn, a rod around which said towels pass, pivotally mounted arms which carry said rod and resilient means for normally holding said arms so that said rod is arranged in a fold of said first towel, said rod being moved forward by said first towel against the action of said resilient means during withdrawal of the

initial part of said first towel and returning to its original position under the influence of said resilient means during withdrawal of the remainder of said first towel to enter a fold of the succeeding towel and prevent it from being withdrawn from said cabinet by said first towel. 5

18. A cabinet for dispensing individual paper towels of the kind which are folded and arranged in such a manner that as a towel is withdrawn from the cabinet a second towel is advanced to the position originally occupied by it, said cabinet having an opening through which the towels are withdrawn and in which the leading end of the first towel is accessible, a member around which said towels pass, said member being arranged in a fold of said first towel, means for normally holding said member in said position, said first towel moving said member forward as it is withdrawn, said member being returned to its original position by said means to enter a fold of the succeeding towel and prevent it from being withdrawn from said cabinet by said first towel, means actuated by said member as it moves forward to position the leading end of the second towel so that it is inaccessible through said opening and means which is automatically operative after a predetermined interval to move the leading end of said second towel to an accessible position. 10 15 20 25

19. A cabinet for dispensing individual paper towels of the kind which are folded and arranged in such a manner that as a towel is withdrawn from the cabinet a second towel is advanced to the position originally occupied by it, said cabinet having an opening through which the towels are withdrawn and in which the leading end of the first towel is accessible, a member around which said towels pass, said member being arranged in a fold of said first towel, means for normally holding said member in said position, said first towel moving said member forward as it is withdrawn, said member being returned to its original position by said means to enter a fold of the succeeding towel and prevent it from being withdrawn from said cabinet by said first towel, 30 35 40 45 means actuated by said member as it moves forward to position the leading end of the second towel so that it is inaccessible through said opening and clockwork which is automatically operative after a predetermined interval to actuate 50 said last named means to effect movement of the leading end of said second towel to an accessible position, said member being operative to wind said clockwork during its forward movements. 55

CHARLES E. KIRCH.
